COMPRESSOR

Herbert W. Dow, Milwaukee, Wis., assignor to
Nordberg Manufacturing Company, Milwaukee,
Wis., a corporation of Wisconsin

Application July 6, 1936, Serial No. 89,181

9 Claims. (Cl. 230—21)

This invention relates to compressors and particularly to unloading devices therefor.

The invention produces an unloader in which the housing for the inlet valve is itself a valve, 5 and is shiftable to (1) interpose the inlet valve between the suction connection and the working space and close a clearance pocket, or (2) interpose the inlet valve as before and open a clearance pocket to the working space or (3) open a 10 by-pass around the inlet valve between the suction connection or inlet valve. In condition (3) it is immaterial whether the clearance pocket is isolated or connected with the by-pass, but the latter arrangement is illustrated. The invention 15 is applicable to connect a plurality of clearance pockets successively with the working space, but a single pocket per working space is sufficient to disclose the invention and is chosen for description because it is simpler. An important feature of the invention is the adaptation to use, 20 according to the invention, of inlet valves of the type disclosed in the patent to Nordberg, No. 1,570,392, granted January 19, 1926.

The invention when applied with one clearance 25 pocket for each working space of a double-acting compressor unloads in five steps as follows:

Full capacity.—(Both ends fully loaded). Both clearance pockets isolated, by-passes closed.

$\frac{3}{4}$ capacity.—(One end fully, the other half 30 loaded). One clearance pocket isolated and the other connected with its working space. By-passes closed.

$\frac{1}{2}$ capacity.—(Both ends half loaded). Both clearance pockets connected with their working 35 spaces. By-passes closed.

$\frac{1}{4}$ capacity.—(One end half loaded, the other fully unloaded). One clearance pocket connected with its working space and corresponding by-pass closed—other by-pass open.

Fully unloaded.—Both by-passes open.

Such an embodiment of the invention is illustrated in the accompanying drawing, in which,—

Fig. 1 is a view partly in elevation and partly in section, showing the unloader set for $\frac{3}{4}$ capacity.

Fig. 2 is a fragmentary view showing the crank end inlet valve housing set to open the by-pass.

Fig. 3 is a fragmentary perspective view of the head inlet valve housing or sleeve.

In the drawing, 6 represents the cylinder cast as a unit with jacket 7 and two clearance pockets, namely, a crank end pocket 8 and a head end pocket 9. The ends of the cylinder are closed 50 by heads 11 and 12 with inlet passages 13 and 14

respectively. The heads are jacketed and jacket spaces appear at 15. Discharge connections are shown at 16 and lead from the discharge valves of any suitable type (not shown). A rod 17 carries piston 18 which is reciprocated in the cylinder 6 by any suitable means such as the usual crank and connecting rod (not shown).

Swiveled in openings in heads 11 and 12 respectively are cylindrical housings 21 and 22 for the inlet valves. These housings each have seat grids 23, guard grids 24, leaf or reed valves 25 and leaf springs 26 constructed substantially according to the disclosure of the Nordberg patent above identified.

Sleeve 21 controls inlet passage 13, passage 27 leading to pocket 8 and passage 28 leading to the crank end working space in cylinder 6. Sleeve 22 controls inlet passage 14, passage 29 leading to pocket 9 and passage 31 leading to the head end working space in cylinder 6.

Sleeve 21 is shifted by a crank 32 and sleeve 22 by a crank 33. Each sleeve has three positions and the center lines for the cranks are indicated in broken lines for the three positions which each sleeve assumes.

In Fig. 1 the sleeve 22 is shown in full loading position, so that port 29 leading to clearance pocket 9 is blanked and the inlet valve is interposed between passages 14 and 31. In Fig. 1 sleeve 21 is shown in half loaded position in 30 which passages 27 and 28 freely communicate, so that the inlet valve is interposed between passage 13 on the one hand and the connected working space and clearance pocket on the other hand. In Fig. 2, sleeve 21 is shown in fully un-loaded position so that passages 13, 27 and 28 freely communicate. Each sleeve may assume 35 each of the three positions.

Each sleeve may be set in each of its three described positions by a corresponding duplex piston motor comprising an outer cylinder, a differential piston working therein and forming a cylinder for a second differential piston. The smaller areas of the two differential pistons are constantly subject to fluid pressure and hence are biased in a downward direction. The admission of pressure fluid against the larger area of either piston overcomes the bias of such piston. When both pistons are down the working space is fully 50 loaded; when one piston alone is up, the working space is partially unloaded and when both pistons are up the working space is fully unloaded.

The duplex piston motors A and B are identical (but reversed left to right as shown). Hence 55

a description of one will suffice. Their components are similarly numbered.

In motor B cylinder 35 is mounted on base 36 which serves as a cylinder head. In the motor is 5 a differential piston made up of the two-diameter sleeve 37 and head 38 bolted thereto. Sleeve 37 forms a cylinder in which the two-diameter piston 39 works. Packing rings are used as indicated. Connecting rods 40 connect pistons 39 10 with respective cranks 32 and 33.

The smaller (annular) working space 41 on the upper side of the outer piston and the smaller (annular) working space 42 on the upper side of the inner piston are constantly connected by port 15 43.

A pipe 44 leads from the receiver (not shown) charged by the compressor. An auxiliary receiver 45 is charged through check valve 46 from this pipe, and is in free communication via pipe 47 and 20 branches 48 with chambers 41 and 42, so that both pistons are given a yielding bias downward.

Pipe 44 leads to the lower end of a regulator cylinder and valve chest 51 beneath a combined piston and valve 52 which is urged downward by 25 weight 53 adjustably mounted on lever 54. Lever 54 is fulcrumed at 55 and reacts on piston 52 through thrust rod 56.

The valve portion of piston 51 is of the balanced 30 piston type and comprises an annular recess 57 and an annular recess 58 which respectively control inlet and exhaust functions, separated by the valve rib 59 which has a substantially zero lap with respect to each of a series of ports leading to the four lower working spaces of the duplex 35 motors A and B. Hence these ports are either connected to supply or exhaust. A slight positive lap is permissible and probably desirable.

The ports just mentioned are serially arranged 40 so as to be controlled successively, one port 61 leading via pipe 62 to the space beneath the outer piston of motor A; port 63 leading via pipe 64 to the corresponding space of motor B; port 65 leading via pipe 66 to the space beneath the inner piston of motor A, and port 67 leading via pipe 68 45 to the corresponding space of motor B.

Observe that pipes 66 and 68 lead to annular 50 spaces 69 formed around the outer piston sleeve 37 and thence via ports 71 to the space below the inner piston 38.

The recesses 57 and 58 connect ports 61, 63, 65 55 and 67 each selectively with supply port 72 to which pipe 47 leads and with exhaust port 73 with which exhaust pipe 74 connects.

Thus as pressure in the main receiver rises piston 52 moves up and admits pressure successively to the working spaces of motors A and B, so that the outer piston of A rises, then the outer piston of B, then the inner piston of A, and finally the inner piston of B. On falling receiver pressure 60 the working spaces are successively vented in reverse order, causing the pistons to descend in reverse order.

To afford increasing resistance to rise of piston 52, it is arranged to pick up successively four 65 weights 75, 76, 77 and 78, just prior to the opening to supply of each of the ports 61, 63, 65 and 67 respectively. The weights 75 to 78 inclusive are normally held in suitably spaced relation by a 70 stepped support 79 as shown.

The exhaust pipe 74 may simply lead to atmosphere but in some cases it is desirable to start the compressor fully unloaded. This is desirable, for example, when the compressor is driven by a 75 synchronous electric motor. To provide for com-

plete unloading regardless of receiver pressure, a three-way valve 81 is interposed in exhaust pipe 74 and connected by branch 82 with pressure pipe 47.

In the normal position shown valve 81 connects 5 pipe 74 to atmosphere and blanks branch 82. In unloading position (indicated in dotted lines) it disconnects pipe 74 from atmosphere and connects it with pressure branch 82. This admits pressure beneath all four pistons of the motors A 10 and B by way of the exhaust passages so that these motors move to unloading position.

The valve 81 might be manually operated, but is shown with a solenoid motor 83, which can be controlled by a push button on the starting panel 15 or may be included in one of the starting circuits so as to shift the valve 81 automatically to unloading position during starting and return it to normal position as soon as normal running conditions are attained.

The operation of the device has been traced in connection with the description. The described arrangement affords a simple construction with desirable operating characteristics. More steps 20 can be secured by using plural clearance pockets and additional positions of the valve sleeves to cut them in serially.

Various other modifications may be made within the scope of the invention as defined in the 30 claims.

What is claimed—

1. The combination of a compressor having a working space; means forming a clearance pocket; means forming an inlet passage; a combined valve and valve housing controlling communication between said working space on the one hand and the clearance pocket and inlet passage on the other hand, said housing being shiftable between a first position in which it disconnects the clearance pocket from the working space, a second position in which it connects the same, and a third position in which it opens a free connection between the working space and the inlet passage; and automatic inlet valve means mounted in said housing for controlling one way flow from the inlet passage to the working space in said first and second positions.

2. The combination of a compressor having a working space; means forming a clearance pocket; means forming an inlet passage; an elongated cylindrical valve housing adapted itself to serve as a valve to control communication between said working space on the one hand and the clearance pocket and inlet passage on the other hand, said housing being rotatable between 55 a first position in which it disconnects the clearance pocket from the working space, a second position in which it connects the same, and a third position in which it opens a free connection between the working space and the inlet passage; and a series of plate type inlet valves mounted in 60 and associated with ports in said housing for controlling one way flow from the inlet passage to the working space in said first and second positions.

3. The combination of a compressor having a working space; means forming a clearance pocket; means forming an inlet passage; a combined valve and valve housing controlling communication between said working space on the 70 one hand and the clearance pocket and inlet passage on the other hand, said housing being shiftable between a first position in which it disconnects the clearance pocket from the working space, a second position in which it connects the 75

same and a third position in which it opens a free connection between the working space and the inlet passage; automatic inlet valve means mounted in said housing for controlling one way flow from the inlet passage to the working space in said first and second positions; and means responsive to pressure developed by operation of the compressor for shifting said housing between said positions.

4. The combination of a compressor having a working space; means forming a clearance pocket; means forming an inlet passage; a combined valve and valve housing controlling communication between said working space on the one hand and the clearance pocket and inlet passage on the other hand, said housing being shiftable between a first position in which it disconnects the clearance pocket from the working space, a second position in which it connects the same, and a third position in which it opens a free connection between the working space and the inlet passage; automatic inlet valve means mounted in said housing for controlling one way flow from the inlet passage to the working space in said first and second positions; two piston motors telescopically arranged with reference to one another; operative connections between the piston of one of said motors and said housing; and pressure responsive valve means serving in response to variations of pressure developed by the compressor to vent, and to admit pressure to both motors, and to vent one motor while admitting pressure to the other, the response of the motors under the three stated conditions serving to shift the housing between its three positions.

5. The combination of a compressor having a working space; means forming a clearance pocket; means forming an inlet passage; a combined valve and valve housing controlling communication between said working space on the one hand and the clearance pocket and inlet passage on the other hand, said housing being shiftable between a first position in which it disconnects the clearance pocket from the working space, a second position in which it connects the same, and a third position in which it opens a free connection between the working space and the inlet passage; automatic inlet valve means mounted in said housing for controlling one way flow from the inlet passage to the working space in said first and second positions; two differential piston motors, the piston of one carrying the cylinder of the other; means for constantly subjecting the smaller areas of both pistons to pressure fluid to bias both pistons; means for operatively connecting the piston of said other motor with said shiftable housing; and pressure responsive valve means having three positions and controlling pressure on the larger areas of the differential pistons and serving in one position to vent both, in another to vent one and admit pressure fluid to the other, and in a third to admit pressure fluid to both.

6. The combination of an unloader having three operative positions; two differential piston motors, the piston of one motor carrying the cylinder of the other; means for constantly subjecting the smaller areas of both pistons to pressure fluid to bias both pistons; means for operatively connecting the piston of said other motor with said unloader; and pressure responsive valve means having three operative positions and controlling pressure on the larger areas of the differential pistons, the valve means serving in one position to vent both, in another to vent one and

admit fluid to the other, and in a third to admit pressure fluid to both.

7. The combination of a compressor having two working spaces; an unloader mechanism for each working space, each unloader having three operative positions in which, respectively, it fully loads the working space, partially unloads the working space according to the position of the unloader; two unloader motor mechanisms, one for each unloader, such mechanism comprising two piston motors telescopically arranged with reference to one another, and operative connections from the piston of one of said motors to the corresponding unloader; and pressure responsive distributing valve means having five positions, in the first of which it vents both motors of both units, in the second of which it admits pressure to one motor of one unit and vents the remaining three motors, in the third of which it admits pressure fluid to one motor of both units and vents the remaining two motors, in the fourth of which it admits pressure fluid to both motors of one unit and one motor of the other unit and vents the remaining unit, and in the fifth of which it admits pressure fluid to both motors of both units.

8. The combination of a compressor having two working spaces; unloading means for each of said working spaces, said unloading means each having three functional positions, in one of which it fully loads the working space, in the second of which it partially unloads the working space, and in the third of which it completely unloads the working space; two motor units, one for each unloader mechanism and each comprising two differential piston motors, the piston of one motor of each unit carrying the cylinder of the other motor of that unit; means for constantly subjecting the smaller areas of the pistons of all said motors to pressure fluid to bias said pistons; means for operatively connecting the piston of said other motor of each unit with the corresponding unloader; and pressure responsive distributing valve means having five operative positions and controlling fluid pressure acting on the larger areas of the four differential pistons of the two motor units, said distributing valve having a first position in which it vents pressure from all four of said larger areas, a second position in which it vents pressure fluid from three of said larger areas and subjects the fourth to pressure fluid, a third position in which it vents one of said larger areas in each of said motor units and subjects the other larger area in each of said motor units to pressure, a fourth position in which it subjects three of said larger areas in the two motor units to pressure and vents the fourth, and a fifth position in which it subjects all four of said larger areas of the two motor units to pressure.

9. The combination defined in claim 8, in which the unloader mechanism for each working space comprises a valve housing which carries an automatic inlet valve for the working space, and means forming a clearance pocket, the valve housing having three functional positions, in one of which it isolates the clearance pocket from the working space to fully load the compressor, in the second of which it connects the clearance pocket with the working space to partially unload the compressor, and in the third of which it opens a bypass around said inlet valve to completely unload the working space.
